FREDERICK EMMONS TERMAN, OF STANFORD UNIVERSITY, CALIFORNIA

INDUCTANCE COIL FOR RADIO FREQUENCIES

Application filed June 15, 1927. Serial No. 198,877.

This invention relates to inductance coils for radio frequencies.

The object of the present invention is to provide an inductance coil for radio frequencies which will have an exceptionally small loss. More specifically, the object of the present invention is to provide an inductance coil in which the losses due to the phenomenon known as "skin effect" are substantially eliminated.

The effective resistance of an inductance coil at radio frequencies is actually many times the resistance the coil offers to direct currents. The increase in resistance for alternating currents is due to a phenomenon known as "skin effect". The effect of this phenomenon causes the current to be unevenly distributed throughout the cross-section of the conductor with which the coil is wound. This uneven distribution of current means that portions of the conductor do not do their share in carrying the current so that the actual current is in reality carried by only a small part of the conductor, with the result that the energy losses are very greatly increased.

The phenomenon of "skin effect" arises from the effects of eddy currents induced in the conductors of the coil. These eddy currents in turn are the result of the fact that some of the magnetic flux lines produced by the coil cut through the material of the conductor. Flux lines which encircle or link with only a part of a complete conductor are termed partial flux linkages. These partial flux linkages induce voltages in a part of the conductor, but not in all, giving an unbalanced voltage in the conductor and this unbalanced voltage sets up eddy currents in the coil. These eddy currents are in such direction as to oppose the main current in parts of the conductor and to aid the main current in other parts so that the net result is to redistribute the current over the cross-section of the wire of the coils. The higher the frequency of the alternating current, the greater the magnitude of the skin effect.

The present invention embodies a coil construction in which the conductor is so shaped and oriented that the partial flux linkages are

reduced to a minimum. Since the losses due to skin effect are produced by the flux lines which surround part but not all of a conductor, the skin effect can be very largely eliminated if the coil is wound in such a way that little or no flux gives rise to partial linkages.

The present invention, together with various objects and advantages thereof, will best be understood from a description of a preferred form or example of a coil embodying the invention. For this purpose, reference is made to the accompanying drawings.

In the drawings:

Figure 1 represents a cross-section of a small coil, of ordinary construction.

Figure 2 represents a cross-section of one form of a coil embodying the present invention.

Figure 3 represents a cross-section of a modified form of a coil embodying the present invention.

Figure 4 represents cross-sections of wire suitable for use in the present invention.

Figure 5 represents cross-sections of other wire suitable for use in the present invention.

Figure 6 represents cross-sections of further wire suitable for use in the present invention, and

Figure 7 represents cross-sections of further wire suitable for use in the present invention.

First referring to Figure 1, which illustrates a coil of ordinary construction, there is indicated in the drawing the approximate distribution of current density by the depth of shading of the wire 2. As will be observed from such drawings, with an ordinary coil the current is concentrated on the inner surfaces of the coil windings. There is also indicated the approximate location of flux lines produced by the coil in which it will be seen that some flux lines such as AA and BB do not completely surround all of the conductors. Such flux lines which encircle or link with only a part of a complete conductor are termed "partial flux linkages". These partial flux linkages expand, contract and reverse in direction with alternating currents, cutting through and across the

metal of the wires 2, inducing voltages and eddy currents therein.

Now referring to Figure 2 of the drawings, 3 indicates a coil form which is so shaped as to provide supports 4 for the coil wire 5 as to position the flat sides of the coil wire 5 parallel to the flux lines 6 developed by the coil so as to substantially eliminate partial flux linkages.

In making the substantially cylindrical coil as indicated in Figure 3, it is thus seen it is necessary to wind the different turns at different angles.

While the preferred form of coil embodying the present invention employs a flat conductor, such as illustrated in Figure 2, oriented to make the flat side of the conductor parallel to the flux that exists at the conductor location, the invention can take a number of different forms. A variety of shapes of conductors can be employed; for example, any sort of a rectangular conductor is suitable to a greater or less extent.

I have illustrated in Figures 4 to 7, inclusive, several different shapes of conductors. In Figure 4, the conductor 7 is of square cross-section. Such a conductor is superior to a round wire. The conductors 7^a, 7^b and 7^c are respectively superior to the form of the conductor 7, as the flatter and thinner the conductor, the less eddy currents will be developed therein.

The conductors 8, 8^a, 8^b and 8^c of Figure 5 are substantially the same as those of Figure 4, except that the sides of the rectangles are wedged. These conductors are suitable for use in the coil of the present invention, generally the ones further to the right being the better.

In Figure 6, the conductors 9, 9^a, 9^b and 9^c are shown as starting with a circular shape and ending with a very flat, oval shape. The flatter the conductors of this form, the better adapted for use in the present invention.

In Figure 7, the conductors 10, 10^a, 10^b and 10^c are represented, which have curved or moon-shaped cross-sections and are progressively thinner towards the right. When this form of conductor is employed, the curvature preferably corresponds to the curvature of the flux lines where the wire is situated, and the forms further to the right, or the flatter forms, are the better adapted for the purposes of the present invention.

Referring to Figure 3, there is shown a modified form of coil-winding, embodying the invention. In Figure 3, a winding form, or core 11, is provided, the surface of which is curved, corresponding to the curvature of the flux, which will be developed by the coil. Thin, flat or slightly curved wire 12 is wound against the surface of such form 11, thereby positioning the conductor or wire 12 parallel to the direction of flux developed by the coil.

If desired, only the inner turns of the coil may be wound in order to be parallel to the flux lines. As will be observed from the forms of the invention shown in Figures 2 and 3, the inner turns of the coil, or the turns near the center, require little or no twisting relative to the coil axis to locate the same in their proper positions. The end turns of the coil have to be twisted to a very great angle with the axis of the coil. The greatest partial flux linkages in an ordinary coil occur at the center of the coil and the losses at the center of the coil are much greater than the losses at the end turns of the coil.

In order to simplify the practical construction of the coil, some of the end turns thereof may be wound with round wire, as the losses thereby induced are not very great.

While the invention has been shown as applied to a single-layer coil, it is of course obvious that it may be applied to a multi-layer coil as well.

It should also be understood that where the coil is to be encased in a shielding container, the magnetic flux lines will be arranged in a somewhat different pattern than exists when the coils are by themselves. In such a case, the windings of the coil must be twisted to parallel themselves with the form of flux that will exist when the coil is in the shielded container.

Preferably, the conductor of the coil is of a ductile nature, such as soft-drawn copper so that it may be readily twisted into successively desired positions.

The present invention may also be applied where several coils are used in combination; for example, as a primary and secondary coil combination. In such a case, the flux lines cutting through the conductors of the coils are produced by currents in both coils, and the flat side of the conductors is made parallel to the resultant flux produced by both coils acting together with their currents.

While the form of low-loss coil for radio frequencies herein illustrated is well adapted to carry out the objects of the present invention, it is understood that further modifications and changes may be made in the coil without departing from the present invention, and the present invention includes all such modifications and changes as come within the scope of the following appended claims.

I claim:

1. An inductance coil comprising a form having a winding surface substantially in line with those flux lines developed by the coil which touch such winding surface and a conductor-winding wound on said surfaces and having a comparatively flat cross-section, the cross-section of each portion of the conductor being thus disposed substantially in line with those flux lines to traverse such portion of the coil.

2. An inductance coil for radio frequencies comprising a conductor-winding of relatively flat cross-section which develops flux lines which are non-parallel, the conductor having its cross-section so twisted that each portion of the conductor lies with its direction of greatest breadth in direction of the flux lines developed by the coil and which traverse such portion of the conductor. 70
- 10 3. An inductance coil for radio frequencies comprising a coil wound from a conductor of relatively flat shape, each portion of the conductor being disposed with its direction of greatest breadth substantially in line with the flux existing at the position of such portion of the conductor. 75
- 15 4. An inductance coil comprising a form having a winding surface each portion of which is substantially in line with the flux existing at the position of such portion of the surface, and a conductor winding wound on said surface and having a comparatively flat cross-section, the cross-section of the conductor being thus disposed substantially in line with the flux lines existing at the position of the conductor. 80
- 20 5. An inductance coil for radio frequencies comprising a conductor winding of flat cross-section which develops flux lines which are non-parallel, the conductor having its different portions twisted so that each portion lies substantially parallel to the flux existing at the position of that portion of the conductor. 85
- 25 6. A radio frequency inductance coil comprising a winding of conductive material having a relatively flat cross section, which winding is adapted when a current is passed therethrough to develop a magnetic field, the flux lines of which are non-parallel, different portions of the conductive winding being in position so that in each cross section of the winding the direction of greatest breadth of the different portions of the winding are in line with the flux lines which 90 will be developed by the windings that pass through such portions of the winding. 95
- 30 7. A radio frequency inductance coil comprising a winding of conductive material having a relatively flat cross section, which winding is adapted when a current is passed therethrough to develop a magnetic field, the flux lines of which are non-parallel, different portions of the conductive winding being in position so that in each cross section of the winding the direction of greatest breadth of the different portions of the winding are in line with the flux lines which will be developed by the windings that pass through such portions of the winding, and a supporting form 100 for supporting the winding with its cross section only disposed. 105
- 35 8. A radio frequency inductance coil comprising a conductor winding in which the conductor is a flat strip and at each point is so oriented as to have the flat side of the strip 110
- 40 115
- 45 120
- 50 125
- 55 130
